BASIL G. AUSTIN, OF HARTFORD, CONNECTICUT, ASSIGNOR TO AUSTIN ORGAN COMPANY, OF HARTFORD, CONNECTICUT, A CORPORATION OF MAINE.

ORGAN STOP MECHANISM.

1,162,274.

Specification of Letters Patent. Patented Nov. 30, 1915.

Application filed March 2, 1915. Serial No. 11,480.

To all whom it may concern:

Be it known that I, BASIL G. AUSTIN, a citizen of the United States, residing at Hartford, in the county of Hartford and State of Connecticut, have invented certain new and useful Improvements in Organ Stop Mechanism, of which the following is a specification.

This invention relates to what I shall for convenience term "organ stop mechanism", the object of the invention being to provide simple means of this character which is effective in action and by which the position of a stop or stops can be reversed; that is to say should the stop be "on" it can be immediately put to "off" or vice versa. While as I have observed the title adopted has been selected for convenience and while the construction is of especial utility in the connection noted, it is conceivable that such construction can be employed with equal advantage in other and different ways.

In the drawings accompanying and forming part of the present specification I have shown in detail one of the several convenient forms of embodiment of the invention which to enable those skilled in the art to practise the same will be set forth fully in the following description.

I do not restrict myself to this disclosure; I may depart therefrom in several respects within the scope of the invention defined by the claims following said description.

Referring to said drawings: Figure 1 is a side elevation of portions of an organ involving stop mechanism constructed in accordance with the invention. Figs. 2, 3 and 4 are elevations as seen from the left in Fig. 1, showing the parts in different positions.

Like characters refer to like parts throughout the several figures.

The different parts may be sustained in any desirable manner. For this purpose the framework shown may be provided, this frame comprising the base member 2 and the block 3 located above the base member, the two being connected by a bracket as 4.

The device includes in its make-up a suitable stop-controlling member, the roller 5 answering satisfactorily in this connection, this roller being in the construction like the rollers shown in Letters Patent 1,073,079

granted to me November 11, 1913, and to which reference may be had. In said Letters Patent there were a number of rollers and each controlled a stop. The roller 5 in the construction is exactly like those shown in my patent. The rollers in the latter, however, were operated by actuating elements on traces whereas the roller 5 is otherwise actuated as will hereinafter appear, having as will be understood two positions. When the roller 5 is in one position, the stop coöperative therewith will be on, whereas when said roller is in the other position, said stop will be off.

To effect the operation of the roller 5 an electrically governed device such as the magnet 16 may be provided, this magnet being fastened to and depending from the plate 7 attached by one or more screws as 8 to the top of the block 3. The armature 9 of the magnet constitutes as will hereinafter appear an actuator having in addition to a swinging movement a lateral one. As shown there is a pin 10 rising from the rear or inner portion of the plate 17 and fitting freely in the tapered opening 11 in the adjacent end of the armature 9, by virtue of which the latter can have the compound movement to which allusion has been made.

The electrical energy for the magnet may be supplied in any desirable manner, for instance by the battery 12 connected as by the wire 13 extending from one pole of the battery to one coil of the magnet 6, the wire 14 extending from the other coil of the magnet and being connected electrically with the contact 15 coöperative with the fixed contact 16 from which the wire 17 leads, the wire 17 being connected to the pole of the battery 12 opposite that to which the wire 13 is connected. The contact 15 is upon a circuit closing member such as the lever 18 which may be operated by foot, hand or otherwise, but which is shown as being in the form of a pedal. In Fig. 3 the contacts 15 and 16 are shown as being separated, so that the magnet circuit is open. By moving the contact 15 against the contact 16 through the action of the lever 18, said circuit will be closed and the magnet as a consequence energized to attract or draw down its armature 9.

Fastened to the shaft or trunnion portion 18 of the roller 5 is the plate 19. It will be clear that on the movement of the said plate 19 the roller 5 will be moved a similar extent.

Pivoted to and rising from the plate 19 at opposite sides of the center of movement thereof and of the roller 5 are pins 20 and 21 adapted to be alternately engaged by the 10 armature 9, and when a pin is thus engaged on the movement of the downward armature, it is thrust down to rock the plate 19 and therefore the roller 5. The forwardly projecting portion of the plate 17 has at its 15 outer end enlarged perforations 22 to receive the free portions of the pins 20 and 21 and to permit lateral movement of said pins.

In Fig. 2 the roller 5 is shown as being in one of its two positions, for example the 20 on or operative position, the stop associated therewith being also on, the pin 21 being under the armature 9, so that when the magnet 6 is energized the armature is drawn down to thrust the pin or rod 21 downward 25 to thereby impart a corresponding movement to the right branch of the plate 19 and therefore swing the roller 5 from the on to the off position. At the same time the pin or rod 20 is thrust upward as shown in 30 Fig. 3 in position to be engaged by the armature 9 when the latter has been laterally moved as will hereinafter appear. Connected loosely to the plate 19 approximately centrally of the points of connection 35 therewith of the two pins 20 and 21 is the spring 23 which extends upward through a notch 24 in the stud or projection 25 extending forward from the block 3 and also through an enlarged hole in the plate 7, 40 being continued upwardly from the plate and projecting freely through a perforation 26 at or near the free end of the armature 9, said spring constituting one of several ways for effecting the lateral movement 45 of the armature 9 or equivalent actuator. On the deenergization of the magnet 6 by the opening of the circuit thereof, the spring 27 promptly returns the armature 9 to its initial upward position as shown in Fig. 1. 50 It will be assumed that the parts are in the positions shown in Fig. 2 and that the magnet 6 has been energized. As already set forth this results in the thrusting downward of the pin 21 by the armature 9, thereby 55 swinging over the plate 19 and roller 5 from the positions shown in Fig. 2 to those of Fig. 3. As the roller 5 oscillates in the manner in question the spring 23 is bowed or tensioned, so that when the magnet 6 is deenergized and its armature 9 elevated by the spring 27, said armature 9 will be moved laterally by the spring 23 over the top of the pin 20 as shown in Fig. 4. If when the parts are in the position shown in Fig. 60 4, the magnet is energized, the pin 20 will

be thrust down and the roller 5 through the described parts moved from off to on and in the last mentioned operation the action already described will be exactly reversed.

What I claim is:

1. The combination of an oscillatory member, an actuator for operating said oscillatory member, and means for moving the actuator laterally into position to apply its effect to said actuator alternately at opposite sides of the center of oscillation thereof. 70

2. The combination of an oscillatory member, an actuator for operating said oscillatory member, and spring means for moving the actuator laterally into position to 80 apply its effect to said actuator alternately at opposite sides of the center of oscillation thereof.

3. The combination of an oscillatory member, pins connected with said oscillatory 85 member at opposite sides of its center of movement, an actuator, and means for moving the actuator laterally into position to engage the pins in alternation.

4. The combination of an oscillatory member, an actuator for oscillating said oscillatory member, and spring means tensioned by the oscillatory member on its movement for moving the actuator laterally into position to apply its effect to the oscillatory 95 member alternately at opposite sides of the center of oscillation thereof. 90

5. The combination of an oscillatory member, pins connected with the oscillatory member at opposite sides of its center of 100 movement, a swinging actuator co-operative with the pins, a spring connected with the oscillatory member approximately centrally between the points at which the pins are connected therewith, the spring acting 105 against the actuator to shift the same alternately in opposite directions laterally to position it for successively engaging the pins and the spring being tensioned by the oscillatory member on the movement thereof. 110

6. The combination of an oscillatory member, an electrically governed member provided with a movable part, said movable part being positioned to oscillate said oscillatory member, and means for moving said 115 movable part laterally and into position to alternately apply its effect to said oscillatory member at opposite sides of the center of oscillation thereof.

7. The combination of an oscillatory member, an electromagnet and its armature, the armature being adapted when attracted to operate said oscillatory member, and means independent of the magnet for moving the armature thereof laterally to position the 125 same for moving the oscillatory member alternately in opposite directions.

8. The combination of an oscillatory member, pins connected with said oscillatory member at opposite sides of its center of 130

movement, an electromagnet and its armature, the armature being adapted to operate the pins, and a spring connected with the oscillatory member and adapted to be tensioned, thereby to effect the movement of the armature laterally in position to alternately engage said pins.

In testimony whereof I affix my signature in presence of two witnesses.

BASIL G. AUSTIN.
